SPRING FOR BI-FOLD DOORS AND THE LIKE

Kenneth E. Hewson, 626 Colony Drive,
Troy, Mich. 48084

Filed July 18, 1973, Ser. No. 380,291

Term of patent 14 years

Int. Cl. D8—08, 09

U.S. Cl. D8—259

Fig - 1

Fig - 2

Fig - 3

Fig - 4

Fig - 5

FIG. 1 is a perspective view illustrating a spring for bi-fold doors and the like showing my new design;

FIG. 2 is a front elevational view thereof;

FIG. 3 is a top plan view thereof;

FIG. 4 is a rear elevational view thereof;

FIG. 5 is a bottom elevational view thereof; and

FIG. 6 is a left-end elevational view thereof and is identical to the right-end elevational view thereof and which right-end view is illustrated in FIG. 1.

I claim:

The ornamental design for a spring for bi-fold doors and the like, as shown.
